US00D830763S

(12) **United States Design Patent** (10) Patent No.: **US D830,763 S**
 Bassill et al. (45) Date of Patent: **** Oct. 16, 2018**

(54) **INDUCTION APPLIANCE**

- (71) Applicant: **HATCO CORPORATION**,
 Milwaukee, WI (US)
- (72) Inventors: **Brandon Bassill**, Malibu, CA (US);
Nick Bassill, Malibu, CA (US); **Mark**
Gilpatric, Milwaukee, WI (US); **Hans**
Wildebush, Milwaukee, WI (US);
Michael Whiteley, Waukesha, WI (US);
Kelly Wright, Ringwood, IL (US);
John Scanlon, Sturgeon Bay, WI (US)
- (73) Assignee: **HATCO CORPORATION**,
 Milwaukee, WI (US)
- (**) Term: **15 Years**
- (21) Appl. No.: **29/624,964**
- (22) Filed: **Nov. 6, 2017**

Related U.S. Application Data

- (62) Division of application No. 29/550,719, filed on Jan. 6, 2016, now Pat. No. Des. 814,848, which is a division of application No. 29/506,842, filed on Oct. 21, 2014, now Pat. No. Des. 751,855.

CLAIM

The ornamental design for an induction appliance, as shown and described.

DESCRIPTION

FIG. 1 is a perspective view of an embodiment of the induction appliance;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings are for illustrative purposes only and form no part of the claimed design.
